(57) **CLAIM**

The ornamental design for a fishing pole light, as shown and described.

DESCRIPTION

FIG. 1 is a perspective view of a fishing pole light;
FIG. 2 is a front elevational view thereof;
FIG. 3 is a rear elevational view thereof;
FIG. 4 is a top plan view thereof;
FIG. 5 is a bottom plan view thereof;
FIG. 6 is a left-side elevational view thereof; and,
FIG. 7 is a right-side elevational view thereof.
The broken line showing of environment in the drawings is
for illustrative purposes only and forms no part of the claimed
design.
